UNITED STATES PATENT OFFICE.

WILLIAM L. BARRELL, OF LAWRENCE, MASSACHUSETTS.

WEFT-REPLENISHING LOOM.

1,308,144.

Specification of Letters Patent.

Patented July 1, 1919.

Application filed May 22, 1914, Serial No. 840,206. Renewed September 19, 1917. Serial No. 192,230.

To all whom it may concern:

Be it known that I, WILLIAM L. BARRELL, a citizen of the United States, and resident of Lawrence, in the county of Essex and State of Massachusetts, have invented certain new and useful Improvements in Weft-Replenishing Looms, of which the following is a specification.

This invention relates to weft-replenishing looms of the same general character as that illustrated and described in Letters Patent 1,221,410 granted me April 3, 1917. The principal features on which the present invention is based are a thread-parting device, and a thread-placing device arranged to move the thread into the range of action of the parting device.

In looms of this general type two shuttles are used alternately, each shuttle upon becoming nearly if not quite exhausted of filling being transferred from the shuttle-box of the lay to a bobbin magazine, and being replaced temporarily by a filled shuttle. The thread-parting mechanism to which the present invention relates is arranged to part the outlying stretch of thread that extends from the fabric to the spent shuttle, and the thread-parting operation is caused to occur before the spent bobbin has been discharged from the spent shuttle, so that when new filling is inserted into the shuttle the eye of the shuttle will have been cleared of old filling.

Of the accompanying drawings:

Figure 1 represents a top plan view, partly in section, of a shuttle, a support therefor, and a shuttle carrier which acts to carry the spent shuttle from the shuttle box of the lay for a new supply of filling and which thereafter carries the filled shuttle back to the shuttle box of the lay.

Fig. 2 represents a transverse vertical section through the structure intersected by line 2-2 of Fig. 1,—the shuttle carrier in Fig. 2, however, being in a different position, as though about to take the shuttle from the loading support to the shuttle box of the lay.

Fig. 3 represents a vertical section through the structure intersected by line 3-3 of Fig. 1.

Fig. 4 represents a vertical section through the shuttle carrier and through a spent shuttle resting thereon.

Fig. 5 represents a top plan view of a spent bobbin, a portion of the fabric in the loom, a stretch of thread running from the

fabric to the spent bobbin, a thread-cutting device, and a thread-engaging device whose function is to move the thread into position to be cut by the cutting device,—these parts being shown in the relative positions which they occupy at the instant when the thread is cut.

Fig. 6 represents, in end elevation, a general view of a weft-replenishing loom in which my improvement is included.

The same reference characters indicate the same parts wherever they occur.

The loom structure shown by Fig. 6 includes a frame 10, lay 11, crankshaft 12, connecting link 13, sword 14, picker 15, and shuttle binder 16, all of well-known structure and arrangement. Two shuttles are shown, that indicated at *x* being in the shuttle box of the lay, and that indicated at *x'* being held in reserve to replace the shuttle in the lay when the filling of the latter is exhausted. The shuttle box of the lay includes a movable front piece 17.

The weft-replenishing mechanism shown by Fig. 6 includes a bobbin magazine 20, shuttle support 21, a bobbin inserter 22, a shuttle carrier 23, a shuttle receiver 24, a cam shaft 25, and other details hereinafter specified.

The loom is provided with suitable clutch mechanism and with suitable automatic clutch-controlling mechanism whereby the shafts 12 and 25 are caused to rotate alternately but never both at once. The mechanism for this purpose is not illustrated, and it will be sufficient to state that so long as there is sufficient filling in the operating shuttle *x* the crankshaft may continue to rotate, but that when the filling in the operating shuttle *x* is exhausted to a predetermined degree the crank shaft comes to rest and the cam shaft is set in operation to the extent of one complete rotation. One rotation of the cam shaft is sufficient to perform a cycle of operations of the weft-replenishing mechanism, and upon the completion of such cycle the cam shaft again comes to rest and the crankshaft is again set in operation.

Assuming that a change of shuttles is necessary in consequence of exhaustion of the filling in the operating shuttle *x*, and assuming further that the crankshaft 12 has come to rest and that the cam shaft 25 has been set in operation, the following actions take place: A cam 26 lifts the shuttle-box

front 17 and actuates a shuttle ejector 27 to transfer the shuttle α to the receiver 24. The receiver then lifts the shuttle α to clear a path for the shuttle α' which is carried by 5 the carrier 23 from the support 21 to the shuttle box of the lay. While the carrier 23 is adjacent the lay, the receiver 24 descends to deposit the spent shuttle α upon the carrier. The shuttle-box front 17 then 10 descends to its initial position, confining the filled shuttle α' in the place formerly occupied by the shuttle α . The carrier 23 then moves to carry the spent shuttle to the support 21, where it is deposited in the position occupied by the shuttle α' as shown by 15 Fig. 6. While the spent shuttle is in the position last stated, the shuttle inserter 22 is depressed to transfer a full bobbin α from the magazine 20 into the shuttle. In this 20 connection it is to be understood that the shuttles used for this purpose are of well-known structure which permits the full bobbin to enter through the top and to force the spent bobbin out through the bottom, 25 the shuttle being provided with suitable gripping means for holding the full bobbin and for permitting the discharge of the spent bobbin.

The fundamental principles as to interchanging two shuttles, and inserting fresh filling into each shuttle as it becomes exhausted is the same in this invention as in that set forth in my said Patent 1,221,410, although there are some differences in the 30 mechanism for accomplishing the results stated. In addition to all these elements and operations the said pending application includes a thread-cutting device arranged to cut the thread which runs from the fabric 35 in the loom to the spent bobbin of the shuttle which has been placed upon the support 21 preparatory to receiving a full bobbin. I have shown a similar thread-cutting device for the same purpose in the drawings 40 of this present application, and the improvement contained in this present application which is not contained in the aforesaid pending application is a thread-engaging device whose function is to move the thread 45 into position to be cut by the cutting device. Referring to Fig. 5, the spent bobbin α' is shown in the relative position which it occupies while in a shuttle and while the 50 said shuttle is resting upon the support 21 preparatory to receiving a full bobbin. The thread α^2 extends from the spent bobbin to the fabric A in the loom. Two co-operative blades 28 and 29 of a cutting device are arranged to cut the thread α^2 at a point close 55 to the shuttle. 30 indicates the thread-engaging device whose function is to move the thread α^2 into position to be cut. The aforesaid pending application does not include 60 any special element like the device 30, and 65 in order to cause the cutting device to act

upon the thread the front side of the shuttle was originally provided with a recess and the cutting device was arranged so that the points of the blades would occupy the said recess whenever the shuttle was upon 70 the support 21 in the position shown by Figs. 1, 2 and 3. With the former arrangement, however, the thread α^2 would sometimes fail to enter between the blades of the cutting device; but having provided the device 30, I avoid the likelihood of such failure. 75

The operating mechanism for the cutting device is substantially the same as in the aforesaid pending application, but a description of the same may not be amiss in the present case. The blades 28 and 29 as shown are integral with relation to each other, being formed with a spring portion 31 whereby they are normally held open to receive 80 the thread. The cutting device is mounted in a holder 32. An arm 33 loosely mounted upon a rockshaft 34 is arranged to lift the blade 28. The blade 28 normally occupies a position lower than that shown by Fig. 3, 85 in which position the cutting edges of the blades are open to receive the thread. The operating movement of arm 33 is caused by the shuttle carrier 23 after the carrier has deposited the spent shuttle upon the support 90 21. For this purpose a rocking member 35 is mounted upon the rockshaft 34 in position to be engaged and actuated by the shuttle carrier. The movement of the member 35 is transmitted to the member 33 by a torsional spring 36. Other devices, fully 95 illustrated and described in said pending application, are operated by the rocking member 35; but the description of such other devices need not be given in this case. 100

The thread-engaging device 30, as shown, is affixed to the shuttle carrier 23. This device is provided with a series of hooks 37, any one of which may catch the thread. This device is so arranged that the hooks extend upwardly into the spent shuttle when the shuttle is upon the carrier in the position shown by Fig. 4. A notch 38 is provided in the lower edge of the front wall of the shuttle to enable the hooks to pass from the shuttle after the forward travel of the shuttle has been arrested by the front of the support 21 and while the carrier 23 continues to move to the position shown by Figs. 1 to 6. 110

The cutting action of the cutting device occurs before the spent bobbin is discharged from the shuttle, and the bobbin thread on the bobbin side of the cutting device is free to be drawn out of the throat of the shuttle 115 by the discharged bobbin to clear said throat for the thread of the fresh bobbin. 120

I claim:

1. In a weft-replenishing loom, means arranged to interchange a spent shuttle and 130

- a filled shuttle, means arranged to insert a full bobbin in the spent shuttle and force the spent bobbin out of said shuttle, means arranged to cut the thread running from the fabric to the spent bobbin, and thread-engaging means arranged to move said thread into position to be cut by said cutting means.
2. In a weft-replenishing loom, means arranged to insert a full bobbin into a spent shuttle and force the spent bobbin out of said shuttle, means arranged to carry the spent shuttle from the shuttle box of the lay to said bobbin-inserting means, means arranged to cut the thread running from the fabric to said spent bobbin, and thread-engaging means arranged to move said thread into position to be cut by said cutting means.
3. In a weft-replenishing loom, means arranged to insert a full bobbin into a spent shuttle and force the spent bobbin out of said shuttle, means arranged to carry the spent shuttle from the shuttle box of the lay to said bobbin-inserting means, means arranged to cut the thread running from the fabric to said spent bobbin, and thread-engaging means carried by said shuttle-carrying means to move said thread into position to be cut by said cutting means.
4. In a weft-replenishing loom, means arranged to insert a full bobbin into a spent shuttle and force the spent bobbin out of said shuttle, means arranged to carry the spent shuttle from the shuttle box of the lay to said bobbin-inserting means, means arranged to cut the thread running from the fabric to said spent bobbin, and thread-engaging means arranged to operate while said spent bobbin is in the shuttle to move said thread into position to be cut by said cutting means.
5. In a weft-replenishing loom, means for supporting a shuttle away from the shuttle box of the lay, means arranged to carry a spent shuttle from said shuttle box to said support, thread-cutting means adjacent said support, thread-engaging means arranged to move the thread, running from the fabric to the spent bobbin in the shuttle on said support, into position to be cut by said cutting means, and means arranged to insert a full bobbin into the shuttle on said support and force the spent bobbin from said shuttle.
6. In a weft-replenishing loom, means for supporting a shuttle away from the shuttle box of the lay, means arranged to carry a spent shuttle from said shuttle box to said support, thread-cutting means adjacent said support, thread-engaging means carried by said carrying means to move the thread, running from the fabric to the spent bobbin in the shuttle on said support, into position to be cut by said cutting means, and
- means arranged to insert a full bobbin into the shuttle on said support and force the spent bobbin out of said shuttle.
7. In a weft-replenishing loom, means arranged to interchange a spent shuttle and a filled shuttle, said means including a shuttle-carrier, means arranged to insert a filled bobbin into the spent shuttle at a position apart from the shuttle-box of the lay, a thread-cutting device, thread-engaging means arranged to move the thread, running from the fabric to the spent shuttle, into position to be cut by said cutting device, and means arranged to be actuated by said shuttle-carrier to operate said cutting device.
8. In a weft-replenishing loom, means arranged to interchange a spent shuttle and a filled shuttle, said means including a shuttle-carrier, means arranged to insert a filled bobbin into the spent shuttle at a position apart from the shuttle-box of the lay, a thread-cutting device, a thread-engaging member carried by said shuttle-carrier and arranged to underlie the bobbin of the spent shuttle to move the thread, running from the fabric to the spent shuttle, into position to be cut by said cutting device, means arranged to arrest the spent shuttle while said shuttle-carrier is moving, to register the spent shuttle in bobbin-receiving position, and means arranged to be actuated by further movement of said shuttle-carrier to operate said cutting device.
9. In a weft-replenishing loom having a change shuttle-box and a thread-parting device, the combination of means arranged to remove the spent shuttle from said shuttle-box, and thread-positioning means having a thread-engaging portion movable into and out of the spent shuttle to move the thread into position to be parted by said device.
10. In a weft-replenishing loom having a change shuttle-box and means arranged to discharge the spent bobbin from the spent shuttle outside said shuttle-box, of means including a shuttle-carrier arranged to transfer the spent shuttle from said shuttle-box to the first said means, a thread-engaging device carried by said shuttle-carrier and arranged to move the outlying thread of the spent shuttle laterally away from the latter, and thread-parting means arranged to part the laterally moved thread between said device and the eye of the shuttle.
11. In a weft-replenishing loom, in combination, a working shuttle and a spare shuttle each having a recess in its front wall, a change shuttle-box, means arranged to interchange the spent shuttle in said shuttle-box and the spare shuttle, means arranged to part the outlying thread of the spent shuttle, and means movable into and out of said recess of the spent shuttle to move said outlying thread into potential

parting position relatively to said parting means.

12. In a weft-replenishing loom, in combination, a working shuttle and a spare shuttle each having a recess in its front wall, a change shuttle-box, means arranged to interchange the spent shuttle in said shuttle-box and the spare shuttle, means movable into and out of said recess of the spent shuttle to displace the outlying thread laterally from the spent shuttle, and means arranged to part said displaced thread between said recess and the delivery eye of the spent shuttle.

13. In a weft-replenishing loom, in combination, a shuttle-box, a shuttle-carrier and operating mechanism therefor arranged to carry the spent shuttle outside the shuttle-box, and thread-parting means arranged to

be operated by said shuttle-carrier to part 20 the thread that extends from the fabric to the spent shuttle.

14. In a weft-replenishing loom having a change shuttle-box, shuttle-changing mechanism including means for removing the 25 spent shuttle from said shuttle-box, means arranged to part the thread that extends from the fabric to the removed spent shuttle, and means arranged to reload said shuttle after the thread has been parted as afore- 30 said.

In testimony whereof I have affixed my signature, in presence of two witnesses.

WILLIAM L. BARRELL.
